Primary Examiner — Ian Simmons*Assistant Examiner* — Carissa C Fitts(74) *Attorney, Agent, or Firm* — Hamre, Schumann, Mueller & Larson, P.C.(57) **CLAIM**

The ornamental design for a grooved wire support for a probe test core, as shown and described.

DESCRIPTION

FIG. 1 is a perspective view of a grooved wire support for a probe test core and showing the claimed design in an unclaimed environment of a bottom of a probe test core.

FIG. 2 is a bottom view thereof;

FIG. 3 is side view that shows some unclaimed environment of the probe test core shown in FIG. 1; and,

FIG. 4 is a top view showing the unclaimed environment of the top of the probe test core shown in FIG. 1.

Surface shading in the FIGS. 1 and 2 is provided to show the character and contour of surfaces of three-dimensional aspects of the design.

The broken line showing is for environmental purposes only and forms no part of the claimed design.
